UNITED STATES PATENT OFFICE.

JOHN ERICKSON, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

ELECTRICAL-IMPULSE-TRANSMITTING DEVICE.

1,023,200.

Specification of Letters Patent. Patented Apr. 16, 1912.

Application filed August 23, 1906. Serial No. 331,700.

To all whom it may concern:—

Be it known that I, JOHN ERICKSON, a citizen of the United States of America, and resident of Chicago, Cook county, Illinois, 5 have invented a certain new and useful Improvement in Electrical-Impulse-Transmitting Devices, of which the following is a specification.

My invention relates to automatic telephones, and more particularly to the rotatable dials or calling devices with which the subscribers are provided.

In my prior application Serial No. 331,304, filed August 20th, 1906, I claimed 15 my invention broadly, while in the present application I have made both broad and specific claims for the form of calling device hereinafter described. In certain respects, therefore, my present application is subordinated to my said prior application.

As hereinafter described and as shown in the drawings, I provide the usual rotatable calling dial with a supplemental or controlling dial, which latter can rotate in a forward direction but not in a backward direction. With this arrangement both dials will rotate in a forward direction, and when the subscriber releases them only the inner or regular calling dial will then rotate back 25 to normal position. This prevents any forcing or acceleration of the backward rotation of the calling dial, inasmuch as the outside or supplementary dial is always positively locked against back rotation. As explained 30 in my said prior application, an arrangement of this character insures the proper transmission of the electrical impulses for operating the switches at the exchange or central station.

40 In the accompanying drawings Figure 1 is a front elevation of a subscriber's calling device embodying the principles of my invention. Fig. 2 is a detail vertical section of the same. Fig. 3 is a detail fragmentary 45 perspective view of a portion of the outer or supplementary dial. Fig. 4 is an enlarged detail sectional view of a portion of the two dials. Fig. 5 is a rear view of the center of the outer or supplementary dial. 50 Fig. 6 is a face view of the central portion of the inner or calling dial. Fig. 7 is a face view of the hub or end portion of the shaft or arbor upon which the two dials are mounted. Fig. 8 shows the mechanism of 55 the calling device with the dial and front of

the casing removed. Fig. 9 is a rear elevation of the mechanism. Fig. 10 is a sectional view showing the toothed wheel or member by which the springs are pressed for transmitting the impulses. Figs. 11 to 16, 60 inclusive, show different positions of the springs and the said toothed wheel, and show how the impulses are transmitted, in the well-known manner.

The inner rotatable dial A is of the usual form or pattern and has its central portion a non-rotatably engaged with the outer end B of the shaft C. This rotatable dial is preferably provided with ten finger openings, ranging from 1 to 0, and with an additional finger opening for long distance calling. The usual stationary finger stop D is provided for limiting the forward rotation of the dial. The supplementary or outer dial or rotatable disk E is axially alined with the said inner disk, both disks being secured to the shaft by a screw or bolt F. The said supplementary or outer disk or calling dial is provided with a circular row of finger openings, whereby the finger openings in the inner or calling disk are always in alinement with a corresponding number of openings in the outer disk or dial. In addition the said outer disk or dial E is provided with an inner circular row of 80 openings, as shown in Fig. 1, whereby the numerals 1 to 0, and the indication for long distance, are always exposed when the outer disk is at rest. In other words, these numerals and long distance indications are always exposed to view when the two disks are at rest. The said outer disk has a peripheral flange provided with teeth e adapted to be lockingly engaged by a hook-shaped dog or pawl e¹, which latter is pivoted to 95 the frame or support e². A spring e³ engages the said dog and keeps the same in engagement with the periphery of the said outer disk or dial E. With this arrangement the said outer disk or dial can rotate 100 in a forward or clockwise direction, but cannot rotate in a backward or counterclockwise direction. This is for the reason that the dog e¹ will allow the teeth e to pass in a forward direction, but will catch and hold 105 the disk E against rotation in a reverse direction.

It will be understood that a spring G is employed for returning the shaft and inner calling disk to normal position. As in all 110

devices of this character, the said shaft is adapted to operate the electrical impulse-transmitting mechanism within the telephone, so as to transmit the impulses for operating the automatic switches at the exchange or central station. With this arrangement the inner rotatable calling dial A is secured rigidly to the said shaft, while the said outer or additional dial is adapted to turn upon said shaft. In this way the calling subscriber can insert a finger through the coincident finger openings of the two disks or dials, and can then rotate both of the dials or disks in a forward direction, 10 the two rotating in unison until the subscriber's finger strikes the stop D. When this occurs it will be seen that the dials cannot be forced back to their normal positions, because the outer dial can only rotate in a 15 forward direction, and such being the case no backward rotation of the inner dial can be effected manually. The calling subscriber can only release both dials when his finger strikes the stop D, thus allowing the 20 outer dial or disk to come to rest, and permitting the inner dial to rotate back to normal position. It will be understood that the electrical impulses are transmitted during this return or back rotation of the inner dial, 25 and that ordinarily it must not thus rotate too fast, as then the electrical impulses will not be properly transmitted. In other words, the arrangement thus provided insures a free and natural return of the dial 30 to its normal position, under the influence of the spring G, and this motion cannot be forced or accelerated. In this way correct and proper use of the subscriber's calling 35 device is always insured.

40 Figs. 8 to 16, inclusive, illustrate the well-known form of subscriber's calling mechanism, in connection with which I have elected to describe my invention. Referring to Fig. 10, it will be seen that the impulse wheel H is mounted on the shaft C, and is adapted 45 to operate the impulse springs I and J relatively to the ground post K, in the well-known manner. Referring to Fig. 2, it will be seen that the spring L operates like a 50 clock spring, and serves to give the impulse wheel and dial a backward rotation. As this mechanism forms no part of my present invention, no further description is necessary.

55 It will be seen that the spring which returns the dial and impulse wheel to their normal positions is not opposed or retarded by the means by which forcing or undue acceleration of the dial is precluded. The 60 outer dial serves as a guard for the inner or numeral-bearing dial, and is locked against rotation in one direction. The inner or regular dial can rotate in both directions, in the usual manner.

65 It will be seen that the outer dial or wheel

E constitutes a means for preventing, to a certain extent at least, stoppage or interruption of the return motion of the impulse wheel H when the latter returns to normal position. In other words, the subscriber 70 must withdraw his finger in order to release the inner dial, and hence he cannot keep his hand on the dial while it is rotating; and thus the outer dial E serves to prevent the stoppage and interruption which previously 75 very often occurred when a subscriber carelessly left his hand on the rotary dial after it started back to normal. For this reason it is not possible for the person operating the mechanism to stop the said impulse 80 wheel, or to interrupt the transmission of impulses, after the said wheel has once started to return to normal position. In other words, when the person using the mechanism once disengages or releases the 85 dial, the mechanism will then continue in operation, and cannot be stopped until it reaches the end of its operation. What I mean by this is that the arrangement tends to protect the mechanism against this sort 90 of thing, as after once releasing the inner dial A it would be difficult for the user of the mechanism to then stop it or interrupt it while returning to its normal position. When the operator once withdraws the 95 finger from the two dials, then the mechanism proceeds to transmit the required impulses, and the person so using the mechanism is not likely to accidentally or deliberately attempt to stop the impulse wheel 100 before it reaches its normal position. Thus, as I say, the outer dial or apertured wheel constitutes a means for preventing stoppage or interruption of the return motion of the impulse wheel.

It will be seen that the outer dial—that is, the dial having the endless series of finger-holes—is always rotated forward from the position where it was left at rest after the previous call. Furthermore, the dial thus rotatable only in one direction is provided with finger-holes each of which is common to all the numerals—that is to say, each hole may serve for different numerals, as in the course of several calls it may pass from one numeral to another. Thus provision is made for changing the relation between the holes of the said dial and the numerals, and with the arrangement shown only a portion of the said series of holes is serving as numeral holes at any one time. In other words, a portion of the said endless series of finger-holes is always out of service.

What I claim as my invention is:—

1. In automatic telephony, the combination of means for transmitting electrical impulses, and means including a plurality of rotatable calling dials for operating said means, one of said dials being rotatable only in one direction.

2. In automatic telephony, the combination of means for transmitting electrical impulses, a calling dial for operating said means, and an outer supplemental dial, each 6 dial being rotatable in a forward direction, but only the inner or calling dial being rotatable back to normal position to transmit the electrical impulses.

3. In automatic telephony, the combination of means for transmitting electrical impulses, an inner calling dial, a spring for returning said calling dial to normal position, an outer or supplemental dial, said dials rotatable together in a forward direction, and a locking device for holding the outer or supplemental dial against backward rotation.

4. In automatic telephony, the combination of a shaft, a spring for rotating the 20 shaft back to normal position, a calling dial secured to said shaft, provided with a series of finger openings ranging from 1 to 0, an outer or supplemental dial loosely mounted upon the said shaft, provided with a circular row of finger openings, and also with a circular row of numeral openings, the finger openings of the inner or calling dial always being opposite a corresponding number of finger openings in the outer or supplemental dial when the two dials are at 30 rest, the said numerals being always exposed to view by a corresponding number of numeral openings in the outer dial when the two dials are at rest, a finger stop for 35 limiting the simultaneous forward rotation of the two dials, and a ratchet device for preventing back rotation of the outer or supplemental dial.

5. In automatic telephony, a subscriber's 40 calling device comprising an apertured disk or calling dial rotatable only in one direction, and means rotatable in the opposite direction for transmitting the impulses.

6. In automatic telephony, a subscriber's 45 calling device comprising a plurality of rotatable dials or apertured disks arranged one in front of the other, and means for preventing back rotation of the outer dial or disk.

50 7. In a telephone system, a rotatable calling dial, a guard disposed in front of the dial to prevent forcing or undue acceleration of the same, and means for locking the guard against movement with the dial in one direction.

55 8. In a telephone system, a rotatable calling dial, a rotatable guard disposed in front of said dial to prevent forcing or undue acceleration of the same, and means for precluding rotation of said guard in one direction.

55 9. A subscriber's calling mechanism comprising impulse-transmitting devices, a rotary dial therefor having an endless series of holes, a member having numerals each of 60 which is always opposite one of said holes when the dial is at rest, and means for preventing backward rotation of the dial.

70 10. A subscriber's calling mechanism comprising impulse springs, means for operating said springs, said means including a dial rotatable in one direction, provided with an endless series of holes and numerals for said holes, and means for preventing rotation of the dial in the other direction.

75 11. A subscriber's calling mechanism comprising impulse springs, means for operating said springs, said means including a dial having an endless series of numeral holes, rotatable for calling purposes from 80 the advanced position where it was left at rest after the previous call, and means for preventing said dial from rotating in a backward direction.

85 12. A subscriber's calling mechanism comprising impulse springs, means for operating said springs, said means including a dial having an endless series of holes, numerals for said holes, and means by which said holes are movable relative to the numerals, 90 so that each hole is common to all numerals.

95 13. A subscriber's calling mechanism comprising impulse springs, means for operating said springs, said means including a dial having an endless series of holes, numerals for said holes, and means for changing the relation between said holes and the numerals.

Signed by me at Chicago, Cook county, Illinois, this 18th day of August, 1906.

JOHN ERICKSON.
